METHOD OF PROTECTING WOODEN PILES

James C. Meem, Brooklyn, N. Y.

Application March 1, 1933, Serial No. 659,073

2 Claims. (Cl. 61—54)

This invention relates to pile structures and has for its general objects the provision of new and improved piles particularly adapted for sub-aqueous use, and to novel methods and apparatus for forming and producing such piles.

The improvements embodying the preferred form and method were particularly designed for protecting, stabilizing and reinforcing piles for foundations in sub-aqueous soils. The features of 10 the invention are adaptable for general application in pile structures. In producing pile foundations in sub-aqueous soils it not infrequently happens that in order to obtain a firm bearing, comparatively lengthy piles have to be driven. When 15 it is practicable and desirable to employ piles made of wood for this purpose, they can be obtained and driven at much less expense than piles of other types. In the case of such wooden piles there is no danger of deterioration for those portions 20 that are in the sub-aqueous soil. However, if any portions of such wooden piles are exposed above the water, whether constantly or intermittently, the piles will in the course of time deteriorate and rot; while, for those portions above 25 the ground but not above the water, there is liability of attack and destruction from marine borers and other causes.

The present invention relates to means and methods for protecting, strengthening and stabilizing exposed portions or areas of such piles. 30 There is the further advantage that by the employment of the invention the bearing value of the pile will be considerably enhanced and also its resistance to the thrust of current, and the chock 35 of ice or heavy floating debris.

In carrying out the invention, a reinforcing envelope of cementitious material such as concrete or the like is formed or placed about the exposed area of the pile by a novel method that is comparatively simple and inexpensive. Substantially 40 the only apparatus required is a hollow metallic element or collar structure which is suitably placed or set around the wood pile, preferably after it has been driven into the soil to a firm bearing. This collar structure constitutes a mold or 45 form for the concrete which is poured into it in a fairly soft condition. Preferably a metallic frame or reinforcement is applied to the exposed portion of the pile prior to the pouring operation. 50 After such operation the concrete envelope is compacted, the projecting portion of the pile cut off, vertical reinforcing bars to engage the superstructure are applied; and finally, after the concrete 55 has sufficiently set, the collar structure or its upper portion is removed and the superstructure which the piling is intended to support is completed as required. This method results in the production of a pile structure which fulfills cheaply and efficiently the requirements, and obviates the defects above pointed out.

The invention will be described in detail in connection with the accompanying drawing, wherein

Fig. 1 is a fragmentary central vertical sectional view of the pile structure and apparatus for producing the same in accordance with my invention;

Fig. 2 is a cross sectional view taken on a plane indicated by the section line 2—2 in Fig. 1;

Fig. 3 is a view corresponding generally to Fig. 1 and illustrating a modified pile structure and apparatus;

Figs. 4 to 8 inclusive illustrate successive steps in the novel method of carrying out the invention to produce the pile structure illustrated in Figs. 1—2;

Fig. 9 illustrates a modification of the method.

In carrying out the invention, a wooden pile 10 of suitable length is set up and driven to proper penetration and resistance in the sub-aqueous soil indicated at S. A steam or air pile driver or hammer P or other suitable means is employed for 20 driving the piles. It will be understood that the illustrated pile 10 is one of a set or series. The pile thus driven extends for some distance above the surface of the water W as illustrated in Fig. 4.

The next step comprises the setting-up of the 25 apparatus or metallic mold. As best illustrated in Figs. 1 and 2 this apparatus or device is a metallic shell or collar element comprising preferably two parts or members 11 and 12. The main or upper collar member 11 preferably has 30 a truncated conical shape with its smaller end upward. The collar member may be made of sheet steel or other suitable material, and is preferably unitary or one piece. It may be strengthened by longitudinally disposed spaced angle bars or reinforcing ribs 13. The lower collar member or base 12 is in the form of a metallic cylinder or annulus of a diameter slightly less than the lower end of the member 11 and is inserted in the bottom portion of said member 11. The members 11 and 12 are detachably secured together and this may be accomplished in any desired manner as by a driving fit, or, if found necessary, wedges 14 may be employed for the purpose, these being 35 driven sufficiently tight to hold the base 12 in 40 place, but also readily to admit of detachment and withdrawal of the main part or section 11 when required. The collar element ordinarily should be from two to three feet in diameter or from one to two feet more than that of the wooden pile it- 45 self. The length of the collar element should be sufficient to reach from some two to five feet below the soil to above the level of the water.

The collar element or devices 11, 12 is greased 50 on its interior and is then set up around the pile as illustrated in Fig. 5. It should be tamped down to a substantially firm seat, this being readily accomplished by the workman if the upper portion of the soil, as is ordinarily the case, is sufficiently yielding. Otherwise it may be found 55

desirable preliminarily to make a shallow trench or seat in the soil along the pile line. Suitable reinforcing devices are then dropped over the upper portion of the pile 10 and attached thereto. These reinforcing devices may be as shown in Figs. 1, 2, 6-8, in the form of a cylindrical metal cage constituted by a series of metal rings 15 spaced apart and connected by light vertical rods or heavy wires 16. The reinforcing cage 15, 16 is supported from the pile 10 by spikes 17 driven into the pile, the top ring 15 resting on the spikes.

Next, concrete indicated at 18, in fairly soft condition is poured into the collar element around the pile 10, the top portion of which as illustrated extends upward well above the top of the collar element. The pile driver P is then set on the pile and operated sufficiently to settle and compact the concrete, particularly at its bearing area. This compacting operation may further drive the pile 10 to a slight extent. The compacting operation tends to settle the concrete, particularly at its lower portion, driving out or downward and compacting the moist soil at the bottom. At the completion of the packing operation the concrete envelope 18 has been thoroughly settled and seated within the mold member or formation 11, 12 from a point well down in the collar section 12 to the top of the main section 11 as illustrated in Fig. 6.

As the next step, the projecting upper portion of the pile 10 is cut off about level with the top of the collar element as illustrated in Fig. 7, and vertically disposed reinforcing bars 19 are driven into the concrete envelope and left sticking up some two feet or as required. The function of these bars is to engage the subsequently erected superstructure and tie it to the pile on which it is to be in part supported.

After the concrete envelope has sufficiently set, usually the next day, the upper collar section 11 is withdrawn, leaving the collar section 12 emplaced. The pile and its associate piles constituting the set when thus erected are in condition to receive and be connected to and support the superstructure which is conventionally indicated in Fig. 8.

The sections 11, after having been withdrawn, may of course be used in subsequent operations. The base 12 which is left in place, functions to support the concrete collar or envelope 18, and is helpful in preventing disintegration of its lower end portion, but under some conditions it may not be necessary or desirable to employ a base portion to be left in and remain part of the primary pile structure.

Further modifications may be resorted to within the scope of the invention. For example, as illustrated in Fig. 3 the mold element of the first described construction may be replaced by a mold element comprising a two-part cylindrical main section, the parts or halves 20 whereof may be flanged at their ends to receive bolts. As shown, these flanges are constituted by angle bars 21, the outstanding flanges whereof are formed with spaced holes to receive connecting bolts 22. These angle bars 21 further function as longitudinal reinforcements and may be supplemented by additional longitudinal reinforcements 23. A base collar 24 similar to that in the first described construction may be employed, the parts 20 and 24 being frictionally connected. The first described construction has certain advantages, as owing to its tapering shape it may

be readily withdrawn upward after the completion of the concrete envelope, and may be made in one piece; whereas the two-part cylindrical construction of Fig. 3 requires to be unbolted beneath water by workmen in order to permit separation of the parts and ready withdrawal. However, under some conditions the two-part cylindrical construction of Fig. 3 may be preferable.

A modification of the method is illustrated in Fig. 9 wherein the collar element, which as there-in shown is of the Fig. 3 construction, is seated in place before the wooden pile is driven, instead of being emplaced after the driving of the pile as in the first described method.

It will be observed that by the present invention there is provided a pile structure comprising a wooden pile proper and an envelope of cementitious material, as concrete, surrounding and protecting the upper portion of the pile proper and secured in fixed relationship thereto, the cementitious material being preferably reinforced and the pile structure as a whole being stabilized and protected; that the pile structure is produced by means of an apparatus or device comprising a hollow metallic form or mold, said mold or form being preferably in two parts, an upper main part and a lower base part, the main part being removable after the envelope has been formed so that it may be repeatedly used in the formation of cementitious envelopes; and that the pile structure is formed by an improved method comprising preferably first driving the pile proper, then emplacing the metallic mold which extends from a point below the top of the sub-aqueous soil to a point above the water, then introducing the concrete, packing or compacting it, and withdrawing the mold after the concrete has set. Other intermediate steps include the leveling of the top of the wooden pile even with the top of the envelope, and inserting connecting devices for connecting the pile or series of piles with the superstructure to be supported thereon.

Various other changes within the scope of the invention, besides those above described, will suggest themselves to those skilled in the art.

I claim:

1. The method of protecting the water-exposed portion of a wooden pile which comprises first driving the wooden pile to proper penetration in subaqueous soil, next dropping over the pile a unitary hollow mold, next driving the mold to a shallow penetration in the subaqueous soil, next placing reinforced concrete in the undewatered space around the pile and inside the mold, and finally after the concrete has set, sliding vertically upward and completely withdrawing the mold as driven.

2. The method of protecting the upper portion of a wooden pile which comprises first driving the wooden pile to required penetration in subaqueous soil, next dropping over the pile hollow form parts one above the other, driving the lower form part to slightly under full penetration in the subaqueous soil, then concreting the space around the pile inside the form to provide a seal and connection between the top of the lower form part and the concrete above it, and then withdrawing the upper portion of the form vertically over the pile from around the hardened concrete, leaving the lower form portion and the concrete contained therein seated where driven.
